ENVELOPE

Joseph A. Chadbourne, Westfield, Mass., assignor
to Old Colony Envelope Company, Westfield,
Mass., a corporation of Massachusetts

Application December 20, 1935, Serial No. 55,448

1 Claim. (Cl. 229—80)

This invention relates to improvements in envelopes and is directed more particularly to envelopes of the type which are commonly called self-sealing.

5 The principal object of this invention is the provision of a novel envelope of the self-sealing type, that is an envelope which may be sealed without the necessity of moistening the adhesive.

According to special features of the invention 10 adhesive is carried by the usual sealing flap as well as by the body of the envelope and this adhesive is of such a nature that when two surfaces carrying the same are brought into contact with one another, they adhere for sealing.

15 The envelope of this invention is so constructed and the adhesive is so located thereon as to facilitate economy in manufacture and means is provided to prevent contact of the adhesive surfaces when the sealing flap is in sealing position and 20 it is not desired to seal the envelope. In this way, a plurality of envelopes may be packed in the usual way without danger of the adhesive surfaces coming into contact with one another when it is not desired to have them do so yet when it is desired to seal the envelope, the means for preventing contact of the adhesive may be readily moved from its protective position or removed entirely 25 from the envelope.

Various other novel objects and advantages will 30 be observed from the following description of the preferred form of the invention, reference being had to the accompanying drawing wherein:

Fig. 1 is a plan view of an envelope embodying the features of the invention with the sealing flap 35 of the envelope in non-sealing position; and

Fig. 2 is a similar view showing the flap in sealing position.

Referring now to the drawing more in detail, the invention will be fully described.

40 The envelope of the invention may take any form or size desired but in any event, it is desirable that the envelope have a front wall portion 2, end flaps 4 and a rear wall 6. The flaps 4 and wall 6 extend inwardly to overlie the back of the 45 front wall 2 in the usual way and preferably the rear wall 6 is secured to the end flaps 4 so as to form the envelope pocket.

A sealing flap 8 is hinged to one of the walls such as the front wall 2 and this is foldable down- 50 wardly as along a line 9 to overlie the side of the envelope opposite to that to which it is hinged. In referring to the rear wall, it will now be understood that the term may include the part 6 or the end flaps 4 or both since these parts constitute a 55 wall as distinguished from the front wall 2.

Adhesive represented by 15 and 16 is applied to the inner side of flap 8 and to the rear wall. In the form shown, the adhesive 16 is applied to the upper part of end flaps 4. The adhesive is of a self-sealing type which does not require moistening but which adheres to itself so that as the adhesive surface on the flap 8 contacts with that on the back of the envelope, it becomes sealed thereto. Various substances may be employed for this purpose, such as rubber dissolved in hydro-carbon 10 liquids, latex, or the like.

As has been described, the adhesive area 16 is provided on the body of the envelope and the sealing flap 8 is so arranged that it may be brought downwardly into sealing position and 15 secured to the body of the envelope. That is to say, the sealing flap 8 is secured in place to the envelope itself in the usual way, yet the usual necessity of moistening the adhesive is obviated.

What may be called a safety member 12 is 20 provided at the upper side of the rear of the envelope and in the form shown it is secured to the upper marginal edge of the wall 6. Preferably a line of perforations 10 is provided between the parts 6 and 12 and this facilitates tearing of the 25 member 12 so that it may be removed from the envelope. In any case, however, the flap is movable so that it may be swung from a position over the adhesive area 16 to a position away therefrom where the area 16 is uncovered and ready 30 for contact with the flap 8. That is, the part 12 may be removed entirely from the envelope by tearing on the line 10 or it may be merely folded back out of the way so that the area 16 is exposed.

The envelopes of the invention are packed or stacked with the member 12 overlying the adhesive 16 as shown in Fig. 1 and with the sealing flap 8 folded downwardly into sealing position. This, of course, prevents contacting of the areas 40 15 and 16 and thus the envelopes may be shipped, stored and otherwise handled in the usual manner without danger of untoward sealing.

When it is desired to use an envelope and seal it, the adhesive 16 is uncovered, as stated, by 45 either removing the part 12 by tearing or by turning it downwardly. Then flap 8 may be brought down to sealing position as shown in Fig. 2 so that adhesive areas 15 and 16 contact and adhere to one another without the necessity 50 of moistening the adhesive.

While I have described the invention in great detail and with respect to a preferred form thereof, it is not desired to be limited thereto since 55 many changes and modifications may be made

therein without departing from the spirit and scope of the invention. What it is desired to claim and secure by Letters Patent of the United States is:

- 5   An envelope of the self-sealing type comprising in combination, a front wall, side flaps extending inwardly from opposite sides of said front wall and overlying the back face thereof, a back wall member extending upwardly from the lower 10 marginal edge of said front wall and overlying the outside of said side flaps, a sealing flap hinged to the upper marginal edge of said front wall and foldable downwardly to the upper part of said back wall member, adhesive areas on said 15 sealing flap and one of said side flaps arranged to register with one another when said sealing flap is folded downwardly, the adhesive on said sealing

flap being adapted to adhere to the adhesive on said side flap upon contact therewith and the said adhesive area on the side flap being normally covered by a certain portion of the back wall member so as to prevent contact of the 5 adhesive areas, and a line of perforations extending through said back wall member to facilitate removal of said certain portion thereof, all adapted and arranged whereby said certain portion of the back wall member may be removed so 10 as to uncover the adhesive area on the side flap and said sealing flap may be folded downwardly so that its adhesive area contacts the adhesive area on the side flap and adheres thereto for sealing said envelope. 15
